United States Patent

Des. 238,039
Patented Dec. 16, 1975

238,039

COMBINED CHILD'S DISH AND BASE THEREFOR

Sven-Eric Juhlin, Gustavsberg, Sweden, assignor to
AB Gustavsbergs Fabriker

Original design application June 19, 1972, Ser. No.
264,251, now Patent No. 233,972. Divided and this
application Feb. 14, 1974, Ser. No. 442,487

Claims priority, application Sweden Dec. 21, 1971

Term of patent 14 years

Int. Cl. D7—01

U.S. Cl. D7—23

THG 2

FIGS 3

FIGS 4

FIG. 1 is a top perspective view of a combined child's dish and base therefor showing my new design.

FIG. 2 is an exploded perspective view thereof.

FIG. 3 is a bottom perspective view of said base.

FIG. 4 is a top plan view of said base.

The bottom of the dish not shown is unornamented.

This is a division of design application Ser. No. 264,251, filed June 19, 1972, and now Pat. No. D. 233,972.

I claim:

The ornamental design for a combined child's dish and base therefor, as shown and described.
